UNITED STATES PATENT OFFICE.

WILLIAM BINNS, OF BRADFORD, ENGLAND, ASSIGNOR OF ONE-HALF TO JOSEPH
DOWNING MANDER, OF BINGLEY, YORK, ENGLAND.

TEXTILE SPINNING, DRAWING, SLUBBING, ROVING, AND THE LIKE MACHINE.

Application filed January 7, 1922. Serial No. 527,687.

To all whom it may concern:

Be it known that I, WILLIAM BINNS, subject of the King of Great Britain, residing in Bradford, in the county of York and 5 Kingdom of England, have invented certain new and useful Improvements in Textile Spinning, Drawing, Slubbing, Roving, and the like Machines, of which the following is a specification.

10 The present invention relates to improvements in textile spinning, drawing, slubbing, roving and the like machines, and is applicable to any machine normally treating textile fibre lying between the carding or opening machine and the finishing spinning device.

According to the present invention a fibre is taken up from a pair of feeding or draft 20 or the like rollers by means of an air stream and is guided by it axially down a passage to the place where it is to be spun or otherwise operated upon.

Means may be provided to prevent the escape of the conducting stream of air at 25 the place where the fibre sliver or end is picked up. This means may comprise a stationary packed surface operating with the rotating feeding surfaces or it can comprise further baffling streams of pressure air preventing leakage at these points.

The present invention is more particularly described with reference to the accompanying diagrammatic drawings, in which:—

Figure 1 is a general arrangement of the 35 invention as applied to a spinning frame.

Figure 2 is a detail of one form of construction in sectional elevation.

Figure 3 is a corresponding view of a modification.

40 Figure 4 is a corresponding plan view of Fig. 3.

Figure 5 is a sectional elevation of a further modification.

Figure 6 is a corresponding plan view of 45 Fig. 5.

Figure 7 is a diagrammatic view of another arrangement.

A pair of drawing rolls 1, 2, of any desired known construction have a guide tube 50 3, arranged below them which leads to the spinning place. Air is led into a chamber 4, formed in the intermediate space between the tube 3, and the two rolls 1, 2, by means of an inlet pipe 5. This chamber or space 4, is 55 packed by means of leather glands such as 6.

It will consequently be seen that the sliver or yarn passing axially down between the two rolls will be taken up by the air stream and must of necessity be conducted down the air tube 3. Consequently a sure feeding of 60 the sliver is obtained even after breakage has occurred without any mechanical or hand operation.

The arrangement shown in Fig. 2, shows the rolls driven by a leather or like band 7, 65 but this may be of any desired form. A plate 8, which may be faced with leather, rubber or the like material closes the back and front of the chamber 4, against leakage. Further the rolls 1, 2, may be slatted and air 70 led in through their centres radially outwards the sole outlet being through the tube 3.

In the construction shown in Figs. 3 and 4, the air chamber is packed by means of a 75 pair of gland members 9, 10, which may be spring controlled and air is led to the space 11, between them from an air trunk 12, which may be in communication with the inlet pipe 13, with a view to preventing leakage at this 80 place. Further air is led in through the hollow spindles 14, of the drawing rolls to pass through passages 15, therein to grooves or spaces 16, arranged between the sides of the drawing rolls and the side walls 17, similarly for packing purposes, that is to say to prevent baffling or packing air pressure preventing leakage at this place of the main current from the conduit 13. One or both 85 of the rolls may be faced with leather or other material such as 18.

A further form of construction is shown with reference to Figs. 5 and 6 where air pressure from conduits 19 is passed to the packing space 20 and also passes to side 95 passages 21, leading into channels or groovings 22, formed in the sides of the drawing rolls, a labyrinth packing so being formed against leakage of the air stream operating the displacement of the sliver or fibre. 100

The construction as applied to cap spinning arrangements of ordinary form is shown with reference to Fig. 7, in which the drawing rolls 23, feed a sliver 24, axially down a rotating tube 25, driven by a band 105 26, or any desired means. This tube 25, extends from a chamber 27, formed as above described and fed with pressure air from a main 28. The air therefore can only escape down the rotating tube 25, and takes the 110

sliver or fibre with it irrespective of its continuity. Spinning is effected by centrifugal force as the sliver passes under the lower edge 29 of the spinning cap 30 to be spun upon a bobbin 31, oscillating up and down being driven by the wharls 32 and supported by a roller 33, in usual manner.

As shown in Fig. 1, the operating air stream may be arranged to pass through a number of spinning devices in series, that is to say, an air stream passing from a main trunk or conduit to the chamber between a pair of drawing rolls 34, leads the fibre axially down the tube 35, which fibre is then spun at this place whilst the air stream exhausts into an enclosure 36, allowing it to pass into the conduit 37, feeding again the next pair of drawing rolls 38.

In the particular arrangement shown the air stream passes from pairs of drawing rolls through pairs of axial passages but of course three or more may be arranged in parallel as desired and can be connected in series.

Any desired means may be used for obtaining a moving air stream that is to say that the air stream will exist by reason of a difference in pressure between two terminal points, this difference being obtained by

difference in pressure either above or below atmospheric pressure as desired.

I declare that what I claim is:—

1. A textile spinning machine comprising drawing rollers, a guide tube having its axis intersecting the line of contact of said rollers, means to spin the fibre at the end of said guide tube, means to convey the textile sliver from said drawing rollers through said tube to said spinning means, and means to pack the sides of said drawing rollers to prevent air leakage.

2. A textile spinning machine comprising drawing rollers, an air tight chamber at the delivery side of said rollers, an outlet tube leading from said chamber having its axis intersecting the line of contact of said rollers, spinning means at the end of said tube and means to establish differences in pressure between said chamber and the outlet end of the tube.

In witness whereof, I have hereunto signed my name this 19 day of Decr. 1921, in the presence of two subscribing witnesses.

WILLIAM BINNS.
